UNITED STATES PATENT OFFICE.

HERMAN SCHROEDER, OF SOLLITT, ILLINOIS.

CONNECTOR FOR ELECTRIC-CURRENT-CARRYING CONDUCTORS.

1,085,497.

Specification of Letters Patent. Patented Jan. 27, 1914.

Application filed April 22, 1913. Serial No. 762,824.

To all whom it may concern:

Be it known that I, HERMAN SCHROEDER, a citizen of the United States of America, residing at Sollitt, in the county of Kankakee and State of Illinois, have invented new and useful Improvements in Connectors for Electric-Current-Carrying Conductors, of which the following is a specification.

10 This invention relates to improvements in connections or coupling devices for the electric current carrying conductors of electric circuits and, in the present instance, is directed particularly to a detachable connector for coupling or connecting the various conductors of a railway train telephone system. It is to be understood, however, that my invention in its useful application is not limited to this particular purpose as the 20 same may be employed wherever it may be advantageously used.

In carrying out the present invention, it is my purpose to provide a connector or coupler for the conductors of a railway train telephone system which will automatically uncouple in the event of the cars of the train becoming disconnected through accident or otherwise without injuring or mutilating the individual conductors so that 30 when the cars are again connected the electrical continuity of the circuit may be established with ease and facility.

It is also my purpose to provide an automatic connector of the type described which 35 will embrace the desired features of simplicity, efficiency and durability coupled with cheapness of cost in manufacture and marketing and which may be readily applied to the cars of a train.

40 With the above and other objects in view, the invention consists in the construction, combination and arrangement of parts hereinafter set forth in and falling within the scope of the claim.

45 In the accompanying drawings; Figure 1 is a view in side elevation of a train equipped with a telephone system in which my improved connectors are installed. Fig. 2 is a fragmentary side elevation of two 50 adjacent or connected cars of a train showing the connector on an enlarged scale. Fig. 3 is a perspective view of the connector or coupler, detached showing the companion members thereof in the positions they 55 occupy when the cars leave each other.

Fig. 4 is a sectional view through the device.

Referring now to the accompanying drawings in detail, A designates a railway train composed of the individual cars a connected together in train formation in any well known or approved manner, while b, b indicate telephone sets installed in the locomotive cab and the caboose of the train respectively, such telephone sets being connected with each other by way of a talking circuit c. This talking circuit is composed of conductors 1, 1 carried by each car of the train and arranged, in the present instance, along the under side of the body of the respective car.

In order to connect the conductors of adjacent cars to one another so as to establish a continuous circuit for the current and at the same time enable the electrical continuity of the circuit to be broken automatically in the event of the cars uncoupling, I dispose between the confronting ends of adjacent cars a connector indicated as an entirety by the reference character C. Each connector is designed to establish connections between the conductors of adjacent cars and embraces companion elements each secured to the bottom of the respective car and hanging loosely therefrom and designed to engage the element to form a unitary connector or coupler. When the cars are disconnected for any reason, the coupling straightens out and subsequently uncouples automatically thereby preserving the individual conductors of the circuit and holding the same intact. The companion elements of the connector are indicated at 2, 2 and each, in the present instance, is composed of a pair of metal bars 3, 3 each having one end thereof formed to provide a partially circular socket 4 adapted to receive the end of the respective conductor, the wall of the socket being then compressed to decrease the diameter of the socket and firmly grip the end of the conductor. The opposite ends of the bars 3, 3 of the companion elements are bent upwardly as at 5 and then curved to form segments 6, 6 having flat surfaces 7 designed to lie face to face contact with the similar surfaces of the segments on the bars of the other elements. Each segment 6 is provided with a keeper 8 preferably formed integral therewith and disposed upon the flat surface thereof to receive a coöperating segment. In 110

the present instance, the bars 3, 3 of each element of the coupling are spaced apart in parallelism by means of a block 9 of suitable insulating material disposed between the 5 bars and suitably secured thereto, while the bars themselves are incased in a section of hose 10 suitably secured to the bottom of the car and depending therefrom. If desired, the hose may be extended the full length of 10 the respective car so as to inclose the conductors of the circuit, although such is not absolutely necessary.

From the foregoing description taken in connection with the accompanying drawings, 15 the construction, mode of operation and manner of employing my invention will be readily apparent. Assuming the cars of the train to be coupled up properly, it will be observed that the companion elements of 20 each coupling hang loosely from the bottom of the cars and the electrical continuity of the circuit maintained so that the trainmen in the caboose may have talking communication with the engineer or vice versa. 25 Should the train part, however, the coupling between the disconnected cars will first straighten out and subsequently uncouple automatically, the companion elements of 30 such coupling swinging upwardly incident to the connections therebetween, while the contacting faces of the segments 6, 6 ride over each other so that the segments leave the respective pieces. Thus, the circuit is 35 automatically broken without mutilating the individual conductors thereof.

It will be seen that I have provided a connector which will be found especially useful

in conjunction with the circuit of railway train telephone systems and which may be readily assembled in circuit formation, the 40 coupling acting automatically to break the circuit without injuring the individual conductors thereof.

While I have herein shown and described one preferred form of my invention by way 45 of illustration, I desire to have it understood that I do not limit or confine myself to the precise details of construction herein described and delineated, as modification and variation may be made within the scope of 50 the claim and without departing from the spirit of the invention.

I claim:

A connector for electric current carrying conductors of railway cars, said connector 55 comprising companion elements hanging loosely from the car body at an angle to the horizontal, each element being formed of a pair of bars spaced apart, each bar having one end thereof bent upwardly and then 60 formed to provide a segment having a flat face adapted to contact with the similar face of the coöperating bar on the other member, means for holding the segments of each pair of bars in face to face contact with the segments of the companion pair, and connections between the opposite ends of said bars and the respective conductors.

In testimony whereof I affix my signature in presence of two witnesses.

HERMAN SCHROEDER.
